UNITED STATES PATENT OFFICE.

CHARLES A. VIDINGHOFF, OF BUFFALO, NEW YORK.

CARD-DELIVERING DEVICE.

1,075,173.

Specification of Letters Patent.

Patented Oct. 7, 1913.

Application filed September 23, 1912. Serial No. 721,836.

To all whom it may concern:

Be it known that I, CHARLES A. VIDINGHOFF, a citizen of the United States, residing at Buffalo, in the county of Erie and 5 State of New York, have invented new and useful Improvements in Card-Delivering Devices, of which the following is a specification.

This invention relates to a device where- 10 by cards bearing advertisements or the like may be fed or delivered successively from a casing containing a pack thereof.

It is the object of this invention to provide 15 a device of this character for advertising or similar purposes which is comparatively simple and durable in construction, which is capable of being operated easily and without liability of getting out of order, which can be readily taken apart for filling the 20 same with additional cards when the same requires replenishing, and which embodies certain other novel details of construction 25 and operation which will be hereinafter more fully set forth.

25 In the accompanying drawings consisting of 2 sheets: Figure 1 is a perspective view of a card feeding device embodying my invention. Fig. 2 is a vertical transverse section thereof taken in line 2—2, Fig. 3. 30 Figs. 3 and 4 are vertical longitudinal sections taken in the correspondingly numbered lines in Fig. 2. Fig. 5 is a horizontal section taken in line 5—5, Fig. 3. Fig. 6 is a perspective view showing some of the parts 35 of the card feeding device detached from each other.

Similar characters of reference indicate corresponding parts throughout the several views.

40 1 represents the cards which are adapted to be fed one at a time from a pack, pile, or stack while the same are arranged within a casing. These cards are preferably of oblong form as shown in the drawings al- 45 though the same may be of any other suitable form if desired, the mechanism of the feeding device being adapted to the particular form of the card. Each of these cards may be provided with any suitable in- 50 scription or printing such as an advertisement of a merchant or manufacturer but the use of this device is not necessarily limited to this purpose.

55 The casing which incloses the pack of cards comprises a fixed rear section and a removable front section which is detachably

connected with the rear section. As shown in the drawings, the fixed rear section consists of an upright rear wall 2 which is preferably secured to a support 3 by means of screws 4 having their heads arranged on the front side of this rear wall so that the same are within the casing and therefore prevent removal of this casing from the support by anyone excepting such persons as have access to the interior of the casing. From the upper edge of the rear wall a top 5 projects horizontally forward and from the opposite vertical edges of this rear wall two upright side walls or flanges 6, 6 project 70 forwardly. The rear wall 2 together with its top 5 and side walls 6 constitute the rear fixed section of the casing and these parts are preferably stamped or bent from a single sheet of metal in any suitable or 75 well known manner.

The front or removable section of the casing comprises an upright front wall 7, two upright side walls 8 projecting rearwardly from opposite vertical edges of the front 80 wall, and a bottom 9 projecting horizontally rearwardly from the lower edge of the front wall, these parts being also preferably stamped or formed of a single sheet of metal. The front section of the casing 85 when assembled with the rear section is arranged with the rear ends of its side walls between the side-walls of the rear section and the bottom of the front section closes the space between the lower ends of the 90 front and rear walls and the side walls of the front and rear casing sections, while the top of the rear section closes the space be- 95 tween the front and rear walls and the side walls of these sections at the upper ends thereof with the exception that the front end of the top 5 stops short of the upper edge of the front wall and thereby forms a transverse outlet slot 10 at the upper front corner of the casing. The pack of cards bears 100 with its foremost member against the rear side of the inner wall and the cards are fed successively upward from the front of the pack and projected through the outlet or slot 10 beyond the top of the casing a suffi- 105 cient distance to permit the upper end of the card to be grasped by hand and withdrawn from the pack. In order to permit of determining from the exterior of the casing whether the supply of cards in the cas- 110 ing requires replenishing a longitudinal slot 11 is formed in the top 5 of the casing

through which the interior of the casing may be visible for the purpose just mentioned.

Various means may be employed for detachably connecting the removable front section of the casing with the fixed rear section thereof. The means, however, which are shown in the drawings for this purpose are suitable and comprise a pair of laterally projecting coupling pins 12 arranged on the rear part of each side wall of the front section and engaging with bayonet coupling slots 13 formed in the side walls of the rear section. These bayonet slots are so constructed that in assembling the front and rear sections of the casing the coupling pins of the front section are first moved rearwardly horizontally into the mouths of the bayonet slots and then upwardly into the legs or angular portions of these slots, whereby the casing section is prevented from being pulled forwardly so long as the front casing section is in an elevated position. The front casing section is maintained normally in this elevated position by means of a spring catch comprising a leaf spring 14 arranged on the inner side of one of the side walls of the front casing section, preferably the right hand wall thereof and secured at its upper end thereto and a locking jaw or pin 15 arranged on the lower end of the spring 14 and projecting outwardly through corresponding openings 16, 17 in the right hand walls of the front and rear casing sections, as shown in Figs. 3 and 6. In order to disconnect the front section from the rear section it is only necessary to push in the locking pin 15 sufficiently to disengage the same from the right hand side wall of the rear casing section after which the front casing section may be moved downwardly and forwardly so that its coupling pins are disengaged from the bayonet or coupling slots of the rear casing section, thereby rendering the interior of the casing accessible for renewing the supply of cards.

The pack of cards is constantly pushed forward so as to compensate for the cards which are successively brought to the foremost position on the pile and fed off therefrom, this being preferably effected by means of a follower or presser plate 18 which bears against the rear side of the pile or stack of cards and a spring 19 interposed between the central part of the follower and the rear wall of the casing so as to exert a yielding pressure against the follower and cause the latter to advance the stack in the same measure as the cards are fed away successively from the front of the stack. The cards are operated upon at their lower edges by the device which causes the upper end of each card to pass upwardly through the outlet slot of the casing. In order to hold the upper and lower edges of each foremost card

of the pack firmly against the front wall of the casing so that the upper end will properly pass out through the outlet slot and its lower end stands in the proper position to be engaged by the feeding off device the follower is so constructed that its pressure is exerted principally in a forward direction against the pack of cards at the upper and lower ends thereof. For this purpose the upper and lower ends of the follower are arranged somewhat in advance of the central or intermediate portion thereof, as shown in Fig. 4. By this means the foremost card is pressed against the front wall of the casing at its upper and lower ends so as to insure properly discharging the same from the casing through the outlet thereof by the feeding-off device.

The mechanism whereby the cards are fed successively from the front of the stack and through the outlet of the casing to a position where they may be grasped by the hand is constructed as follows: 20 represents a vertically swinging feed rock lever which is pivoted on the outer side of the front wall of the front casing section at one side of the center thereof so that its inner arm terminates at about the center of this front wall while its outer arm projects laterally from the side of the casing. Adjacent to the inner arm of the feed lever the casing is provided in its front wall and bottom with a slot or passageway 21 through which a feeding pin 22 projecting rearwardly from the inner arm of the feed lever is adapted to move vertically. The feed rock lever is normally turned and yieldingly held in a position in which its feeding pin is arranged below the path of the pack of cards, this being preferably accomplished by means of a spring 23 connecting the outer arm of the rock lever with the adjacent part of the front casing section. The outer arm of the lever is provided with a rearwardly projecting attaching pin 24 for receiving one end of the spring 23 and the adjacent side wall of the front casing section has an attaching ear 50 stamped bodily therefrom for the reception of the other end of this spring, as shown in Figs. 2, 3, 5 and 6. For the purpose of holding the inner arm of the rock lever in position for causing its feeding pin to engage properly with the foremost card of the pack a guide or guideway 25 is arranged on the adjacent part of the outer side of the front casing section which guide receives a guide finger 26 on the inner arm of the rock lever. The lower end of this guideway forms a stop 27 which limits the turning movement of the rock lever under the action of the spring 23 and arrests the same when the feeding pin has passed below the path of the stack of cards. This feeding pin is equal in length or nearly so to the thickness of the cards which are to be fed

in this device. When it is desired to take a card from the pack in the casing it is only necessary to depress the outer arm of the rock lever until the movement of the same in this direction is arrested, this being effected by the guide finger striking the stop 51 formed by the upper end or shoulder of the guideway 25. During this movement of the rock lever its feeding pin moves upwardly through the passageway 21 of the casing and engages with the lower edge of the foremost card whereby the same is moved upwardly from the pile or stack so that its upper end projects through the outlet at the top of the casing. Upon releasing the rock lever the spring 23 returns the same to its normal or retracted position preparatory to feeding the next card from the stack. In order to prevent the feeding pin 10 from catching the lower edge of the follower lower in the event of the supply of cards becoming exhausted this follower is provided in its upper and lower edge with clearing notches 28 either one or the other of which will be in line with the path of the feeding pin in the foremost position of the follower plate and thereby prevent interference between this feeding pin and the follower regardless of whether one end or the other of the follower is arranged lowermost. Furthermore, by providing the follower plate with clearing notches 28 at both its upper and lower ends it is unnecessary for the attendant who fills the casing with new cards to exercise any particular care in placing the follower against the pack of cards inasmuch as no interference occurs in either position of the follower with reference to the feeding pin of the rock lever.

For the purpose of preventing tampering with this feeding device and either breaking the same, or rendering it inoperative it is desirable to cover up the exposed working parts with the exception of the handle on the outer arm of the rock lever, and to also lock the several parts in such manner that only an authorized person or one having a suitable key is capable of detaching the parts for the purpose of refilling the casing with cards or for inspecting, repairing or adjusting any of the working parts. The preferred means for accomplishing this purpose are constructed as follows: A cover is provided comprising an upright front wall 29 which is normally arranged in front of the casing but separated therefrom by an intervening space, a lower horizontal flange 30 extending rearwardly from the lower edge of the front cover wall and past the lower end of the space between the cover and casing, an upper inwardly turned flange 31 extending from the upper edge of the front cover wall to the upper front corner of the casing, and two upright side walls 32 projecting rearwardly from opposite vertical

edges of the front cover wall and along the outer sides of the side walls of the casing. In its right hand side wall the cover is provided with a slot 33 through which the outer arm of the rock lever projects so that the same can be manipulated at will. At their upper horizontal edges the side walls of the cover are provided with inwardly turned flanges 34 which overhang the lateral or longitudinal edge portions of the cover 75 of the casing. The cover is detachably connected with the casing preferably by providing the rear vertical edges of its side walls with bayonet or coupling slots 35 which are engaged with the coupling pins 80, 12 of the casing by first moving the cover horizontally rearward and then dropping the same so as to interlock these bayonet slots with the coupling pins, as shown in Fig. 1. In this position of the cover the upper flange of its front wall closes the space between this front wall and the front wall of the casing at the top thereof and the lower flange extends past the lower end of this space and underneath the rock lever, 90, thereby preventing easy tampering with the feed mechanism. The upper flanges of the side walls of the cover, in this position also engage with the longitudinal edge portions of the casing cover so as to prevent the latter 95 from being lifted so long as the cover is held in its position. The cover is held by a locking device which preferably consists of a padlock 36 having its bail 37 adapted to pass through co-inciding openings 38, 39 formed in the lower edge of the right hand side wall of the cover and a lug 40 depending from the adjacent side wall of the front casing section, as shown in Figs. 1, 2 and 3. It will thus be noted that when the front casing section and the cover are locked together in the manner described that the cover cannot be lifted and that the front casing section cannot be lowered, thereby preventing disconnection of the front casing section 105 from the rear casing section and also preventing disconnection of the cover from the front casing section, thereby holding the several parts in their proper assembled position and preventing tampering with the working parts by anyone mischievously inclined, whereby the parts are maintained in proper condition for effectively delivering the cards from the pack in the casing when 110 115 120 125 130.

For the purpose of indicating the contents of the casing suitable instructions or an advertisement may be displayed by a card 41 which is arranged behind a transparent pane 42 extending across an opening 43 in the front wall of the cover, as shown in Figs. 1, 3, 4 and 5.

I claim as my invention:

1. A card delivering device comprising a casing adapted to hold a pack of cards and

- having a fixed section composed of a rear wall, a top and two side walls, and a removable section having a front wall, a bottom and two side walls adapted to engage 5 with the side walls of the fixed section, said top being separated from the front wall by an intervening space in the assembled position of the parts to form an outlet for the cards, means for removing said cards 10 successively from the pack through said outlet, and means for detachably connecting the fixed and removable sections of the casing comprising bayonet slots arranged in the side walls of the fixed section and adapted 15 to receive coupling pins on the side walls of the removable section.
2. A card delivering device comprising a casing adapted to hold a pack of cards and having a fixed section composed of a rear wall, a top and two side walls, and a removable section having a front wall, a bottom and two side walls adapted to engage 20 with the side walls of the fixed section, said top being separated from the front wall by an intervening space in the assembled position of the parts to form an outlet for the cards, means for removing said cards 25 successively from the pack through said outlet, and means for detachably connecting the fixed and removable sections of the casing comprising bayonet slots arranged in the side walls of the fixed section and adapted 30 to receive coupling pins on the side walls of the removable section and a catch arranged 35 on one side wall of the removable section and engaging with an opening in the adjacent side wall of the fixed casing section.
3. A card delivering device comprising a casing adapted to receive a pack of cards 40 and provided with an outlet for said cards, and means for feeding said cards successively from said pack through said outlet comprising a rock lever pivoted on the front wall of said casing and provided on its inner arm with a feed pin which is movable in a slot in the front wall of the casing and adapted to engage 45 successively with the edge of the foremost card of the pack and push the same through said outlet.
4. A card delivering device comprising a casing adapted to receive a pack of cards and provided with an outlet for said cards, means for feeding said cards successively from said pack through said outlet comprising a 50 rock lever pivoted on the front wall of said casing and provided on its inner arm with a feed pin which is movable in a slot in the front wall of the casing and adapted to engage successively with the edge of the foremost card of the pack and push the same through said outlet, and a guide on the front wall of the casing for the inner arm of said lever.
5. A card delivering device comprising a 55 casing adapted to receive a pack of cards
- and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage successively with the edge of the foremost card of the pack and push the same through said outlet; and a spring 70 pressed follower adapted to engage with the rear side of said pack of cards and provided with a slot adapted to receive the feed pin of said lever. 75
6. A card delivering device comprising a 80 casing adapted to receive a pack of cards and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage successively with the edge of the foremost card of the pack and push the same through said outlet, and a cover having a front wall arranged in front of said removable casing section and extending over the inner part of said lever. 85
7. A card delivering device comprising a 90 casing having fixed and removable sections adapted to receive a pack of cards and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage 95 successively with the edge of the foremost card of the pack and push the same through said outlet, and a cover having a front wall arranged in front of said removable casing section and extending over the inner part of said lever. 100
8. A card delivering device comprising a 105 casing having fixed and removable sections adapted to receive a pack of cards and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage 110 successively with the edge of the foremost card of the pack and push the same through said outlet, and a cover having a front wall arranged in front of said removable casing section and extending over the inner part of said lever and provided with two side walls arranged outside of the side walls of said casing sections. 115
- 120
- 125
- 130

provided at their upper edges with inwardly turned flanges which overhang the top of said fixed casing section.

9. A card delivering device comprising a casing having fixed and removable sections adapted to receive a pack of cards and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage successively with the edge of the foremost card of the pack and push the same through said outlet and a cover having a front wall arranged in front of said removable casing section and extending over the inner part of said lever and provided with two side walls arranged outside of the side walls of said casing sections and provided at their upper edges with inwardly turned flanges which overhang the top of said fixed casing section and the front wall of said cover being provided at its lower edge with a flange extending rearwardly underneath said lever and the bottom of said fixed casing section.

10. A card delivering device comprising a casing having fixed and removable sections adapted to receive a pack of cards and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage successively with the edge of the foremost card of the pack and push the same through said outlet, and a cover having a front wall arranged in front of said removable casing section and extending over the inner part of said lever and provided with two side walls arranged outside of the side walls of said casing sections, one of the side walls of the cover being provided with a slot for receiving the outer arm of said lever.

50 11. A card delivering device comprising a casing having fixed and removable sections

adapted to receive a pack of cards and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage successively with the edge of the foremost card of the pack and push the same through said outlet, and a cover having a front wall arranged in front of said removable casing section and extending over the inner part of said lever and provided with two side walls arranged outside of the side walls of said casing sections, the side walls of said cover being provided with bayonet slots which receive the coupling pins of the side walls of the fixed casing section.

12. A card delivering device comprising a casing having fixed and removable sections adapted to receive a pack of cards and provided with an outlet for said cards, means for feeding said cards successively from said pack through said outlet comprising a rock lever pivoted on the front wall of said casing and provided on its inner arm with a feed pin which is movable in a slot in the front wall of the casing and adapted to engage successively with the edge of the foremost card of the pack and push the same through said outlet, and a cover having a front wall arranged in front of said removable casing section and extending over the inner part of said lever and provided with two side walls arranged outside of the side walls of said casing sections, the side walls of said cover being provided with bayonet slots which receive the coupling pins of the side walls of the fixed casing section and means for locking said cover and removable casing section against detachment from the fixed casing section.

Witness my hand this 20th day of September, 1912.

CHARLES A. VIDINGHOFF.
